UNITED STATES PATENT OFFICE.

RUDOLPH ZIMMERMANN, OF NEW YORK, N. Y., ASSIGNOR TO HERMAN SCHEUER, OF SAME PLACE.

DESIGN FOR A FAN.

SPECIFICATION forming part of Design No. 23,498, dated July 24, 1894.

Application filed June 14, 1894. Serial No. 514,608. Term of patent 3½ years.

To all whom it may concern:

Be it known that I, RUDOLPH ZIMMERMANN, a citizen of the United States, residing at New York, in the county and State of New York, have invented and produced a new and original Design for Fans, of which the following is a specification.

This design has for its object to provide a novel and ornamental fan, and the leading feature thereof consists in a fan having radial leaves, the edges of each of which are provided with concavities and convexities extending to a rounded point at the outer extremity.

The design is illustrated by the accompanying drawing, in which the figure is a plan view of the fan.

In the drawing the letter A indicates the body of one of the fan leaves. As all the leaves are identical and radiate from a common center, I do not deem it necessary to place the reference letters on more than one of the leaves.

The leaves are each formed with edges B and C. The edges B are curved concave, 25 and the edges C are curved convex, while the remaining portions of the edges comprise the convex curves D, convex curves E and rounded point F at the outer extremity. The leaves radiate from one end of a handle M 30 having straight edges G and curved edges H, I, K, and L.

The design provides a novel and ornamental fan which presents a characteristic and distinguishing appearance to the eye. 35

What I claim is—

The design for a fan, substantially as shown and described.

In testimony whereof I have hereunto set my hand in the presence of two subscribing 40 witnesses.

RUDOLPH ZIMMERMANN.
